(57) **CLAIM**

The ornamental design for a LED tail light, as shown and described.

DESCRIPTION

FIG. 1 is a front perspective view of a LED tail light, showing my new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof;

FIG. 8 is an enlarged detail view of the area 9 in FIG. 1;

FIG. 9 is an enlarged detail view of the area 9 in FIG. 3;

FIG. 10 is an enlarged detail view of the area 10 in FIG. 3;

FIG. 11 is an enlarged detail view of the area 11 in FIG. 3;

FIG. 12 is an enlarged detail view of the area 12 in FIG. 4;

FIG. 13 is an enlarged detail view of the area 13 in FIG. 5;

FIG. 14 is an enlarged detail view of the area 14 in FIG. 6;

FIG. 15 is an enlarged detail view of the area 15 in FIG. 6;

and,

FIG. 16 is an enlarged detail view of the area 16 in FIG. 7.

The broken lines in the drawings illustrate the portions of the LED tail light, which form no part of the claimed design.

1 Claim, 16 Drawing Sheets
